US00D948639S

(12) **United States Design Patent** (10) Patent No.: **US D948,639 S**
Ach et al. (45) Date of Patent: **** Apr. 12, 2022**

(54) **REHABILITATION DEVICE**

- (71) Applicant: **ROM TECHNOLOGIES, INC.**,
 Brookfield, CT (US)
- (72) Inventors: **Samuel Marcus Ach**, Portland, OR
 (US); **Doug Golenz**, Littleton, CO (US)
- (73) Assignee: **ROM TECHNOLOGIES, INC.**,
 Brookfield, CT (US)
- (**) Term: **15 Years**
- (21) Appl. No.: **29/764,219**
- (22) Filed: **Dec. 29, 2020**

Related U.S. Application Data

- (62) Division of application No. 29/717,404, filed on Dec. 17, 2019, now Pat. No. Des. 907,143.
- (51) **LOC (13) Cl.** **21-02**
- (52) **U.S. Cl.** **D21/663**
- (58) **Field of Classification Search**

Primary Examiner — Khawaja Anwar*Assistant Examiner* — Julice Seung Eun Oum*(74) Attorney, Agent, or Firm* — Dickinson Wright, PLLC; Stephen A. Mason; Michael E. Noe, Jr.**CLAIM**

The ornamental design for a rehabilitation device, substantially as shown and described.

DESCRIPTION

FIG. 1 is a top isometric view of a rehabilitation device.

FIG. 2 is a front view of the device of FIG. 1.

FIG. 3 is a rear view of the device of FIG. 1.

FIG. 4 is right side view of the device of FIG. 1.

FIG. 5 is a left side view of the device of FIG. 1; and,

FIG. 6 is a top view of the device of FIG. 1.

The dashed lines form no part of the claimed design.
